DESIGN FOR A DISPLAY STAND

Elliott Leew, Jamaica, N. Y., assignor to Jacques Kreisler Manufacturing Corporation, North Bergen, N. J., a corporation of New Jersey

Application April 23, 1941, Serial No. 100,585

Term of patent 3½ years

To all whom it may concern:

Be it known that I, Elliott Loew, a citizen of the United States, residing in Jamaica, Long Island, county of Queens, and State of New York, have invented a new, original, and ornamental Design for a Display Stand, of which the following is a specification, reference being had to the accompanying drawing, forming a part thereof.

Fig. 1 is a front view in elevation of a display stand, showing my new design.

Fig. 2 is a side view thereof in elevation.

I claim:

The ornamental design for a display stand, as shown.

ELLIOTT LOEW.
